(57) **CLAIM**

The ornamental design for a wheelbarrow, as shown and described.

DESCRIPTION

FIG. 1 is a perspective view showing my new design for a wheelbarrow;

FIG. 2 is a front view thereof;

FIG. 3 is a rear view thereof;

FIG. 4 is a left side view thereof, the right side view being a mirror image thereof;

FIG. 5 is a top view thereof;

FIG. 6 is a bottom view thereof; and,

FIG. 7 is perspective bottom view thereof.

The broken lines in the figures represent portions of the wheelbarrow that form no part of the claimed design.
